UNITED STATES PATENT OFFICE.

LEMUEL W. SERRELL, OF PLAINFIELD, NEW JERSEY.

WASHING DEVICE.

1,151,832.

Specification of Letters Patent. Patented Aug. 31, 1915.

Application filed December 8, 1914. Serial No. 876,050.

To all whom it may concern:

Be it known that I, LEMUEL W. SERRELL, a citizen of the United States, and resident of Plainfield, in the county of Union and State of New Jersey, have invented certain new and useful Improvements in Washing Devices, of which the following is a specification.

My invention is an improved device for receiving soap and subjecting the same to the action of water for the production of a soapy washing medium, and operates on the novel principle of bringing the water into contact with the soap in the form of an atomized spray, whereby suds are formed readily and copiously and with the least consumption of soap and hot water. In prior devices water has been delivered against soap in streams, of larger or finer sizes, but in my invention the soap is acted upon by water in the form of individual, minute or mist-like particles, whereby a specially effective and economical operation is secured.

The particular object of the invention is to provide a simple, effective, low-cost and thoroughly practical brush device for washing dishes, but it will be manifest that the essentials may be embodied in various other forms for various specific purposes.

Numerous novel features of construction and arrangement of a more detailed character will become apparent as the specification proceeds.

In the accompanying drawings illustrating the invention: Figure 1 is a side view of the device, shown in substantially actual size; Fig. 2 is a view partly in front elevation and partly in vertical section; Fig. 3 is a top plan view of the brush; Fig. 4 is a section on the line 4-4 of Fig. 1, on an enlarged scale; Fig. 5 is an enlarged horizontal section on the line 5-5 of Fig. 4; Fig. 6 is a fragmentary detail view, taken on the line 6-6 of Fig. 5; and Fig. 7 is a detail view of the valve member.

The specific embodiment of the invention shown in these drawings will now be briefly described.

A conical casing 2 constitutes a soap and spray chamber, and carries at its lower and larger end a removable brush member 3. The latter has an apertured back 4, provided with a metal rim 5, which has a rolled screw-thread to engage with a corresponding thread 6 in the lower end of the casing. The said rim is shown flanged at the bottom,

and between this flange 7 and another flange 8 on the bottom of the casing is received a rubber guard ring 9. The soap 10, which is introduced into the casing upon removal of the brush member, rests upon ribs 11 molded or otherwise formed upon the brush back. A conical jacket 12 surrounds the conical body of the casing, being supported thereon by means of spacers 13. At the upper end 14 the casing has a tubular neck 14, in which is secured a plug 15 having a single, central, restricted orifice 16; and the water delivered downwardly from this orifice is caused to disperse into atomized or mist-like spray, in which the soap at the bottom of the chamber is bathed, as hereinafter more particularly described. At the upper or narrow end of the casing is a laterally projecting handle 17, which preferably extends upward at a slight inclination from the casing, as shown in Fig. 1. The base of this handle, shown formed as an enlarged ball 18, is provided with a transverse cavity 19, a cavity 20 opening downwardly therefrom and a water connection orifice 21 opposite the handle. In the transverse cavity 19 is secured a cylindrical valve body 22, having end screw caps 23 and 24 and a recess 25 in its under side, into which the upper part of the plug 15 is screwed, thereby supporting the soap and spray chamber and brush device. In order to minimize the heating effect, the internal formation of the handle base 18 is preferably such that air spaces are left between its walls and the contained metal parts, the regions of contact being advantageously confined to the caps 23 and 24. The valve body 22 is formed with its ends hollow, inclosing chambers 26 and 27, which are connected through the central portion of the body by a passage 28. In the latter is disposed a valve member 29 having double seating portions 30 and 31, coöperative with corresponding seats at the ends of the passage 28 and connected by squared guide portions 32 and a central reduced cylindrical portion 33. An inlet port 34 opens into the side of the passage 28 leading from the end of a water connection nipple 35, designed to receive a flexible tube 36. Communication between the passage 28 and the chambers 26 and 27 is established alternately according to the position of the valve, and the chamber 26 is connected with a cavity 37 above the plug 15 by means of longitudinal ports 38, shown more particularly in Fig. 6 and indicated in Fig.

4. The interior of the said plug 15 is hollow, comprising an upper cylindrical portion and a lower tapering portion, the latter, marked 39, terminating in the orifice 16.
- 5 Within the plug is a member 40, having a cylindrical, spirally-grooved portion 41 occupying the upper part of the cavity in the plug and a tapering tip 42 spaced from the wall of the lower cavity 39, so as to leave a
- 10 restricted chamber above the orifice 16.

The cap 24 which closes the chamber 27 is provided with a spring barrel 43, which is covered at its outer end by a rose or multiple stream outlet 44. Between the rose and the 15 adjacent end of the valve is confined an expansion spring 45 for holding the valve in the normal position shown in Fig. 4, that is to say with communication established through a conduit extending from the connection 35 and terminating in the orifice 16, communication to the chamber 27 and the external stream outlet being cut off. The opposite cap 23 has a central opening and a gland 46, through which operates the stem 20 of a plunger button 47 having its inner end in operative relation to the valve, so that by pressure inward on the button the valve portion 30 may be seated and the portion 31 unseated, with the result that the discharge 25 through the atomizer is stopped and that through the external rose 44 opened.

In use, the device is connected with a hot water faucet by means of the tubing 36, and when the water is turned on it flows 30 through the connection 35 and port 34 to passage 28, thence into chamber 26, and by way of ports 38 to the atomizer, where rotary motion is imparted to it before emerging from the orifice 16, with the result 35 that it is delivered over the soap as an issue of minute drops, substantially filling the interior of the casing. The contact of the water with the soap under these conditions is especially effective in forming suds, and the 40 amounts consumed, both of water and soap, are comparatively small. The resulting suds and soapy water flow through the openings in the brush back and between the bristles onto the surface being cleaned. The relatively 45 large area for outlet as compared with the small inlet orifice and consequently small volume of water passing through the device insures against flooding of the soap chamber and therefore permits the drops to 50 strike against the soap. The conical form of the casing enables the device to be introduced into glasses and the like and worked around with a circular rocking movement, in order that the brush bristles 55 may thoroughly cleanse the corners, the rubber guard 9 preventing injury to the article being washed. After each article has been cleaned by the action of the brush and suds, the device is turned sidewise and the user 60 presses on the button 47, in order to dis-

charge clear water from the rose 44 for rinsing.

The handle is preferably of relatively non-heat-conducting material, and the jacket 70 12 surrounding the conical casing is a valuable safety provision, preventing burning of the fingers by contact with the heated wall of the soap and spray chamber.

The construction, formation and relation of the parts are such as to render the device 75 as a whole compact, neat in appearance, and convenient to operate, and at the same time adapt it for inexpensive methods of manufacture. In the construction of the valve body and its therewith assembled parts, substantially 80 all the pieces can be made cheaply and expeditiously on screw machines, and the necessity for relatively costly castings is avoided.

What I claim as new is:

1. A device for washing, comprising a casing containing a chamber adapted to receive soap and having one or more outlets, a water supply connection united with the casing, a restricted inlet orifice to the chamber from said water connection, the inlet area being small as compared with the outlet area, and means in rear of said orifice to cause the water emerging therefrom to disperse in atomized spray over the soap. 95

2. A device for washing, comprising a chamber having one or more outlets and a soap support at its lower portion, and means above the soap support for projecting an issue of atomized spray into contact with the soap, the outlet area being ample as compared with the small volume of water passing through the device whereby flooding of the chamber is avoided so that the spray may be delivered upon the soap. 105

3. In a device for washing, the combination of a means for holding soap, a brush united therewith, a water connection, means for delivering the water in atomized condition over the soap, and outlets of relatively 110 large aggregate area whereby the soap is bathed in the atomized spray and the liquid and suds escape freely into the brush.

4. A dish-washing device, comprising, in combination, a conical casing adapted to receive soap and tapering toward the top where it is provided with a handle, a circular brush mounted at the bottom of the casing where opening is afforded for escape of liquid and suds, and a water connection 120 at the top of the casing, whereby the device is adapted to be worked about in the interior of a glass.

5. A device for washing, having a connection for attachment of a flexible water conduit and containing a soap and spray chamber, a brush element at the bottom of the chamber where relatively free outlet is provided for liquid and suds, and means for delivering the water from said connection over 130

soap in the chamber comprising a restricted orifice small in relation to the outlet area and means in rear thereof to cause the emerging water to disperse in atomized spray.

6. A dish-washing device having a handle whereby it may be held in the hand of the user and provided with a water connection and comprising a double casing adapted to receive soap and having a restricted inlet orifice for water, suitable means for causing the water emerging from said orifice to dis-

perse in atomized spray over the soap, and a brush attached to the casing and provided with outlet openings having an aggregate area materially greater than that of the inlet.

In testimony whereof I have signed my name in the presence of two subscribing witnesses.

LEMUEL W. SERRELL.
